UNITED STATES PATENT OFFICE

JOHN G. GAREIS, OF PHILADELPHIA, PENNSYLVANIA.

BOOKBINDING.

1,023,834.

Specification of Letters Patent.

Patented Apr. 23, 1912.

Application filed March 3, 1911. Serial No. 612,047.

To all whom it may concern:

Be it known that I, JOHN G. GAREIS, a citizen of the United States, and a resident of the city of Philadelphia, county of Philadelphia, and State of Pennsylvania, have invented certain new and useful Improvements in Bookbindings, of which the following is a full, clear, and complete disclosure, reference being had to the accompanying drawings, forming a part of this specification.

This invention relates to book bindings and more particularly to that class in which a portion of the binding serves to form a pocket and another portion, the flap therefor.

One object of the invention is the construction of a forwardly opening pocket on one side of a book and provided with a flap or closure therefor extending freely from the forward portion of the book.

Another object is to extend the binding of the book freely from around the back thereof to form a pocket between itself and the book and within the pocket thus formed to secure a series of alternately folded layers of suitable material, one layer forming the inner side, and another a partition for the pocket, to secure the opposite ends of the extensions to the adjacent ends of the innermost side of the pocket and to secure a flap to the inner side of and operative to close the pocket.

Further objects of the invention are to provide a simple, inexpensive book of the character herein described and of such design and appearance as to make it serviceable as a prayer book, diary, text book or the like, embodying a receptacle for coins, bills, memoranda, etc., besides other improvements on the present art such as will appear in the following specification.

In the drawings, Figure 1 is a perspective view of a book embodying the invention; Fig. 2 is a section on the line 2—2 of Fig. 1, with the flap open and the pocket in expanded position; Fig. 3 is a fragmentary sectional view of the upper corner of the pocket adjacent to and including a part of the back, omitting the signatures and looking toward the forward or free edge of the cover, the back being swung into extreme open position; Fig. 4 is a fragmentary, sectional view of the upper corner of the free edge of the pocket looking toward the rear or hinged edge of the cover and showing the flap in

open position and broken off; and Fig. 5 is a section on the line 5—5 of Fig. 2 looking in the direction of the arrow. The general divisions of the book will be considered as comprising a top 5, bottom 6, front 7, back 8 and sides 9 and 10 respectively.

As shown in Figs. 1 and 2, the invention comprises mainly a body portion 15 comprising signatures bound at the rear and rounded to form outwardly projecting flanges 16 and 17, of which the latter is the greater, the flanges forming recesses in which the board cover on one side and the pocket on the other side lie.

Around the back portion of the book is secured the binding material 18, which passes at one side around the flange 16, forwardly along the outer side of the board 19 to the edge thereof, where it is turned inwardly and terminates at a point 20. Covering and shielding the end 20 of the binding is a lining 21 for the board 19, which extends from the front to the back thereof, is bent at 22 and extends forwardly again to form one flyleaf 23 of the book. At the opposite side 10 of the book, the binding 18 projects around the flange 17 to form a section 26, which extends forwardly to a point 27 where it is bent inwardly to inclose and secure the forward edge of a section of lining 28. The lining 28 extends rearwardly along the inner side of the section 26 of the binding to a point 29 where it is bent forwardly to form a loop 30, from the opposite rear extremity 31 of which it again extends forwardly to a point 32 to form a cover 33 for the signatures. The loop 30 constitutes a partition for the space between the section 26 and the side 33 of the cover. Similar to the construction on the side 9 of the book the lining 35 of the cover 33 extends rearwardly and is bent at 36, from which point it extends forwardly to form the fly-leaf 37.

From the construction just described, it is seen that there is formed a pocket between the section 26 of the binding and the cover 33 on the side 10 of the book, and further, it is obvious that the pocket is divided by the forwardly looped portion 30 to form two adjacent compartments inclosed at the upper and lower ends in a manner hereinafter described.

The flap for the plurality of pockets comprises a section of suitable material 40 secured between the cover 33 and the lining

35 thereof, and extending outwardly to a point 41 where it is folded back upon itself, to include the outer extreme edge of a piece of stiffening material 42, which in turn extends somewhat short of the outer edge of the pockets. A lining 43 is provided for the flap and at its outer extremity covers the in-turned edge portion of the flap 40 while its innermost extremity 44 projects into the 10 pocket adjacent to the main book for a short distance. Having secured the flap in a closed position to the section 26 of the binding, there is provided a glove fastener, the male member 50 of which is secured through 15 the section of binding 26 and the lining 28 thereof, and the female member 51 of the fastener is secured through the flap 40, section of stiffening material 42 and lining 43 thereof.

20 The manner in which the upper and lower extremities of the pockets are inclosed is clearly illustrated in Figs. 3 and 4, which are views of parts of the upper rear and forward corners of the pockets. Referring 25 to Fig. 3 the back portion of the binding material 18 is shown as being turned in at its upper longitudinal edge 55. The material 18 also embodies a larger inwardly bent portion 56 extending forwardly from the 30 back of the book the entire length of the pockets and securing together the upper edges of the lining 28 thereof, the double thickness of the partition 30, and the two thicknesses 60 and 61 of the gusset 62. The 35 gusset 62 extends as shown downwardly from under the inwardly folded edge portion 56 of the forwardly extending portion of the binding material, and is bent upwardly to a point even with the upper level of the portion 56 as at 62, thus forming the gusset. The inner thickness 60 of the gusset terminates at 63, while the outer thickness 61 continues up and over the extremity 63, also including the cover 33, and is secured beneath the 40 upper edge of the lining 35 thereof. The several thicknesses of material just described are secured together and to the back portion of the binding by means of a short strip of suitable material 64, which extends from beneath the lining 35 of the cover 33 rearwardly and is secured to the rear portion 18 of the binding. This describes the construction of the upper gusset 62 inclosing the pockets exactly similar to that which is employed with the gusset inclosing the lower extremities of the pockets.

45 In Fig. 4 is shown the construction employed in securing the upper gusset 62 to the adjacent parts thereof, and it will be noticed that this figure is taken looking in the opposite direction to that of Fig. 3 and also shows that the upper extremity of the flap 40 is folded inwardly upon itself at the edge 65.

50 From the foregoing description it is ob-

served that a book is provided with longitudinal flanges on the rear edges thereof, in front of which, portions of the binding and a pocket are secured. Further, the pocket is formed by the prolongation of the binding 70 from around the back of the book and spaced from the cover adjacent the signatures thereof, and that the upper and lower extremities of the pocket are inclosed by gussets. And still further, that a flap is provided for the 75 forward open end of the pockets, which comprises a piece of suitable material secured to the forward edge of the cover on the pocket side of the book and extending outwardly therefrom. However, it is not desired to limit this invention to the precise 80 details of construction and arrangement herein set forth, as it is obvious that various modifications may be made therein without departing from the essential features of the 85 invention as defined in the appended claims.

Having thus described the invention, it is desired to protect by Letters Patent:

1. A book cover having a board on one side, a back, a forward extension of the material of said back on the opposite side, a section of material folded alternately in opposite directions to form the other side of the cover, a partition and a lining for said extension. 90

2. A book cover having a board on one side, a back, a forward extension of the material of said back on the opposite side, a section of material folded alternately in opposite directions to form the other side of the cover, a partition and a lining for said extension, and gussets securing said extension to the other side of said cover, at the ends thereof. 100

3. A book cover having a board on one side, a back, a forward extension of the material of said back on the opposite side, a section of material folded alternately in opposite directions to form the other side of the cover, a partition and a lining for said extension, gussets securing said extension to the side of said cover at the ends thereof, a flap secured to said cover side, and means to secure the outer portion of said flap to said extension. 110

4. A book having flanges at the side edges thereof, one of said flanges being of greater width than the other, a cover board on the side of said book having the smaller of said flanges, and a forwardly opening pocket formed of layers of folded material on the opposite side of said book and abutting the greater of said flanges. 120

5. A book having flanges at the side edges thereof, one of said flanges being of greater width than the other, a cover board on the side of said book having the smaller of said flanges, a forwardly opening pocket formed of layers of folded material on the opposite side of said book and abutting the greater of 130

- said flanges, and a flap for said pocket secured to one of said layers and extending freely therefrom.
6. A book cover having side boards; a back, a forward extension of the material of said back on one side, gussets securing the ends of said extension to one of said boards, said gussets being integral projections from the opposite sides of said extension, and a flap comprising a member secured along the forward edge of the board adjacent to said extension.
7. A book cover having a board on one side, a back, a forward extension of the material of said back on the opposite side, a section of material folded alternately in opposite directions to form the other side of the cover, a partition and a lining for said extension, and gussets securing said extension to the last-named side of the cover, at the ends thereof, said gussets being integral projections from the opposite sides of said extension.
8. A book having flanges at the side edges thereof, one of said flanges being of greater width than the other, and a cover comprising a forwardly opening pocket formed of layers of folded material on the side having the greater of said flanges.
- 30 9. A book having flanges at the side edges thereof, one of said flanges being of greater width than the other, a cover comprising a forwardly opening pocket formed of layers of alternately folded material on the side having the greater of said flanges, and a flap secured along the forward edge of the inner-
- most of said layers and extending freely therefrom.
10. A book having flanges at the side edges thereof, one of said flanges being of greater width than the other, a cover comprising a forwardly opening pocket formed of layers of accordion-folded material arranged on the side having the greater of said flanges, a flap secured along the forward edge of the innermost of said layers and fastening means for said flap on the outermost of said layers.
11. A book cover having a board on one side and a back, the material of said back extending forwardly on the side opposite to said board, an accordion-folded section of material forming the other side of the cover, a partition and a lining for said extension, and means securing the rearward creases of said accordion section to said back.
12. A book cover having a board on one side and a back, the material of said back extending forwardly on the side opposite to said board, an accordion-folded section of material forming the other side of the cover, a partition and a lining for said extension, and gussets securing said extension to the last-named side of said cover at the ends thereof.

In witness whereof, I have hereunto set my hand this second day of March, A. D., 1911.

JOHN G. GAREIS.
